Attnys.*

UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

HOSIERY AND METHOD OF MAKING THE SAME.

Application filed March 21, 1919. Serial No. 284,200.

To all whom it may concern:

Be it known that I, GEORGE P. BOSWORTH, a citizen of the United States, and a resident of Central Falls, in the county of Providence and State of Rhode Island, have invented an Improvement in Hosiery and Methods of Making the Same, of which the following description, in connection with the accompanying drawings, is a specification, 10 like characters on the drawings representing like parts.

This invention relates to hosiery and to method of making the same, and has particular reference to fashioned hosiery.

15 The object of the invention is to provide a fashioned or properly shaped stocking that is capable of being produced cheaply and in a simple manner and which embodies distinctive features that materially enhance 20 the attractiveness and durability of the stocking.

To the accomplishment of the said object and such other objects as may later appear, my invention comprises a novel construction and method of producing the same as 25 hereinafter described, and particularly pointed out in the claims, reference being had to the accompanying drawings wherein is shown one form of stocking embodying 30 my invention.

In the drawings:

Fig. 1 is a side elevation of a finished stocking made in accordance with any invention;

35 Fig. 2 is a perspective view of the preferred form of blank from which my stocking is made; and

40 Fig. 3 is a development of another blank of slightly modified construction and from which the stocking embodying my invention may be formed.

The invention relates more particularly to a stocking wherein the blank is made either wholly or in part in strip formation and 45 later seamed along one side only of the leg and foot thereof, and I shall described the invention with particular reference to its formation upon a circular knitting machine, but it is to be distinctly understood 50 that the construction thereof is not limited to this or any other form of knitting machine, but within the purpose and scope of my invention the stocking may be knitted by hand or otherwise.

The stocking embodying my invention 55 when knitted by machine may be produced by rotary and reciprocatory movements of the needle carrier, or it may be produced entirely by reciprocatory movements thereof. The preferred method, however, involves both a rotary and a rotary reciprocatory movement of the needle cylinder, and in carrying out this method of constructing the blank I preferably start the knitting of the stocking blank at the toe and upon only 60 a portion of the needles which preferably are arranged in a circular series, the entire complement thereof being just sufficient to knit the largest portion of the stocking blank, that is the tubular portion at the 65 top of the leg thereof.

The number of needles employed in the formation of the tube may vary according to the size and texture of the stocking, but, as an example, in the present case it is assumed 70 that there are three hundred needles in the full set, while the foot and ankle portions may be formed upon, say, two hundred needles. It is, however, to be distinctly understood that the invention is not 75 limited to the use of the number of needles specified, but that the number may be varied according to the size, texture or the nature of the fabric to be produced.

Assuming that the glove is to be formed 80 upon a circular knitting machine by both reciprocating and rotary movement of the cylinder, knitting may be and preferably is started upon the smaller number of needles, namely the two hundred, and at the toe of 85 the stocking blank, to form a course extending from the point 4 along the curved lines 90 5 and 6 to the point 7 (see Fig. 2). The direction of the first course of knitting is, however, immaterial, as it may be started in 95 the opposite direction from that indicated, depending upon the point or time, during the operation of the machine, at which the change is made from rotary to reciprocatory motion.

When the point 7 is reached the motion 100 of the cylinder is reversed and a second course is knitted into the first, until the opposite edge 4 of the strip of fabric is reached, when the motion of the cylinder is again reversed, and this reciprocating movement continues upon the partial set of needles until the point 8 in said strip is reached, where the

narrowing of the toe pocket 9 begins. This narrowing operation is effected in the usual well known manner, that is by withdrawing from action substantially one-half of the 5 needles previously employed in forming the strip and then by gradually withdrawing needles at opposite ends of the operative series of needles until a sufficiently narrow course has been knitted. The needles that 10 have, during the knitting of said narrow courses, been withdrawn from action retain their loops, and when these needles are subsequently brought into action in a reverse order to knit widening courses, the 15 loops retained thereby will be interlooped with those of corresponding narrowing courses to form seams 10 and 11. When the toe pocket has been completed, the needles that were withdrawn previous to the forming 20 of said pocket, are restored to action and reciprocating knitting proceeds on said needles to knit a strip including the instep 12 and arch 13 of the foot.

During the formation of the strip, including the instep and arch portions of the stocking, the rotary reciprocating movements of the needles produce selvage edges at 14 and 15, and these edges are subsequently seamed together along one side only of the stocking. 25 In the present instance, the formation of a blank for a right-hand stocking is being described, that is, the seam is preferably to be formed upon the left-hand or inner side thereof, but where a left-hand stocking is 30 to be formed the operations will be reversed and the seam will be formed upon the opposite side of the stocking.

Although I have shown and described the 40 seam as having been formed upon the inside of the stocking, it is to be distinctly understood that the invention is not limited to this arrangement, but within the purpose and scope of my invention the seams may be formed upon the outer side thereof.

Upon the completion of the instep and arch portions of the foot strip and when the 45 ankle 16 is reached, the usual heel pocket 17 is preferably formed by the well known narrowing and widening operations previously described in connection with the formation of the toe pocket 9. Following the 50 completion of the heel pocket, the inactive instep needles are restored to action and knitting proceeds upon all of the two hundred needles employed in previously forming the arch and instep of the foot strip, to 55 form the ankle strip 20, and this strip also has opposite selvaged edges 21 and 22 which are subsequently seamed, as in the 60 case of the edges 14 and 15.

Having completed the formation of the 65 ankle strip I now proceed to knit the calf portion of the leg, and during the formation of this portion of said leg the strip is gradually increased in width so as to fashion

the same. This is preferably accomplished by automatically picking into operation by any of the well known forms of pickers certain needles at the ends of certain courses. If it is desired to rapidly increase the width 70 of the strip, the needles may be picked into operation at the ends of consecutive courses, or if it is desired to make the increase in width of the strip less rapid, said needles may be inserted after a certain number of 75 intermediate courses have been knitted. It is, however, to be distinctly understood that the particular manner and the rapidity with which the needles are brought into action may be varied within the scope and pur- 80 pose of this invention.

The point at which the widening of the strip hereinbefore referred to takes place, is preferably indicated at 23 and I preferably add the new needles to the courses at 85 one side only of the strip constituting said calf, preferably the rear side 24 thereof, and this I do in order to retain the forward edge 25 substantially parallel with the front line 90 of the stockings, so that all of the fullness produced by the insertion of said needle may be produced at the rear of the stocking.

By the time the top of the calf of the leg portion of said stocking has been reached, 95 the largest number of needles will be in use. In other words, the full complement of three hundred needles will have been brought into action and about the time the last of these needles is being brought into action the machine preferably automatically shifts from a rotary reciprocatory motion to a rotary movement, and knitting continues from the point 26 indicating the upper end of the calf of said leg, to the top 27 of the stocking, 100 thereby producing the seamless tubular portion 28.

Having completed the formation of said tube, the seaming of the stocking may now be effected by starting either at the top or 110 at the toe of the stocking. Preferably, however, I first seam across the toe portion uniting the edges 5 and 6 and subsequently seam together the edges 14 and 15 and the edges 21 and 22 to the fashioned calf portion of 115 the stocking, uniting the edges 24 and 25 thereof to the point 26, where the circular knitting begins.

It is not essential that the stitching operation be discontinued at the point 26, but it 120 may, if desired, be continued along the tubular portion 28 to the top of the stocking, as I have indicated in Fig. 1.

As I have previously stated, the blank 125 from which the stocking embodying my invention is produced may be formed either on a reciprocating machine or a machine which operates to produce a portion of the blank by reciprocating motion, and the remaining portion thereof by rotary or circu- 130

lar knitting, and I have illustrated in Fig. 3 a blank which may be produced entirely by reciprocating knitting.

I preferably, though not necessarily, begin the knitting of this blank at the toe and upon less than the whole number of needles, say two hundred needles. This I do by knitting a plurality of courses starting at either side of the strip 33 preferably at 29, and proceeding to the point 30, and so on back and forth across the strip, until the line 31 is reached, which line represents the first course of the toe pocket 32. Here the narrowing for the toe pocket begins in 15 the usual well known manner and as described in connection with the form of blank illustrated in Fig. 2, and after narrowing and widening of the toe pocket has been completed, on only a part of the needles 20 used to form the strip 33. I then restore to action the balance of the two hundred needles and continue the knitting of the strip until the line 34 is reached, which line represents the juncture of the heel pocket 25 35 with said strip 33. At this time approximately one-half of the active needles are withdrawn from action and knitting continues to produce the narrowing and widening courses of the heel pocket 35 in the 30 usual well known manner, and after this has been completed I again restore to action the balance of said needles and continue the knitting of the strip to a line 36—37, 35 preferably indicating the juncture of the angle 38 with the calf portion 39 of the blank.

I now proceed to knit preferably by gradually lengthening the series of needles for a sufficient number of courses to form 40 the fashioned calf of the stocking, and this may be accomplished either by adding one or more needles in successive courses, or by skipping one or more courses and then adding a needle or needles. Preferably, however, the needles which are added during 45 the gradually lengthened courses, are added at one side only of the strip, preferably at the right of Fig. 3, indicating the edge of the rear portion of the calf of the leg, thus 50 adding fullness to the rear rather than to the front of the leg. The gradual lengthening of the courses continues until all of the needles of the cylinder have been brought 55 into action, and this is accomplished when the top of the calf of said stocking has 60 been reached, which point is indicated at 40. From this point on to the top 41, knitting of the strip by reciprocating knitting continues upon the full complement of 65 needles.

Both edges of the strip 33 from the points 29 and 30 to the top 44 thereof, are selvaged, and these edges are subsequently stitched or seamed together to form the seam 42 illus-

trated in Fig. 1, said seam preferably extending from the first narrowing course of the toe pocket to the top of the stocking. The fabric of the strip from the line 31 to the line 29—30 is superfluous fabric which is later raveled back to the point where 70 seaming of the toe is to be effected, and the line indicating this seam is shown in Fig. 1 at 43.

I desire it to be distinctly understood that although I have described the operation of 75 knitting the blanks for the stocking as beginning at a certain point in the toe so as to form a seam across the top, it is within the scope and purpose of my invention that the seam thereof may obviously extend across the bottom of the toe.

Having thus described one illustrative embodiment of my invention, I desire it to be understood that although specific terms are employed they are used in a generic and descriptive sense and not for purposes of limitation, the scope of the invention being 85 set forth in the following claims:

1. A fashioned stocking having a continuous seam extending along one side only of the foot and leg portions thereof, the stocking being otherwise seamless.
2. A fashioned stocking having a continuous seam extending along the inside only of the foot and leg portions thereof, the 95 stocking being otherwise seamless.
3. A fashioned stocking having a continuous seam extending along the inside only of the foot and leg portions to the top of the calf thereof, the stocking being otherwise 100 seamless.
4. A fashioned stocking having toe and heel portions formed by narrowing and widening, and a continuous seam extending from said toe portion along one side only 105 of the foot, ankle and calf portions thereof, the stocking being otherwise seamless.
5. A stocking having a seamless, tubular leg, a calf portion fashioned at one side, angle and foot portions formed in a continuous strip, the edges of said strip being stitched together to form a continuous seam extending along one side only of said stocking, the stocking being otherwise 110 seamless.
6. A knitted stocking having foot, ankle and calf portions formed in a continuous strip, one edge of said calf portion being fashioned the edges of said strip being seamed together along one side only of said 115 stocking to form a continuous seam, and a seamless, tubular, upper leg portion forming a continuation of said calf, the stocking being otherwise seamless.
7. A knitted stocking having a foot, ankle and calf portion formed in a continuous opposite selvaged strip, one edge of said calf portion being fashioned the edges of said strip being stitched together to form 120

125

a continuous seam along one side only of said stocking, the stocking being otherwise seamless.

8. A stocking blank having foot, ankle and calf portions formed in a continuous strip by reciprocating knitting, the edges of said strip being selvaged and adapted to be stitched together along one side only of the stocking thus providing a continuous 70 seam, and a seamless, tubular leg portion formed as a continuation of said calf portion by rotary knitting, the stocking being otherwise seamless.

9. The method of knitting a fashioned stocking, which consists in forming upon a portion of a series of needles a strip of fabric constituting the foot and ankle portions of the stocking, then in knitting upon a series of needles that is gradually increased in number at one end only to form a fashioned calf, and then in knitting upon all of the needles a tubular portion constituting the leg of the stocking. 75

10. The method of making a stocking, which consists in knitting upon a portion of a circular series of needles and by reciprocating knitting, a strip of fabric constituting foot and ankle portions of the stocking, then in knitting upon a series of needles that is gradually increased in number at one side only and by reciprocating knitting to form a fashioned calf as a continuation of said ankle portion, and then in knitting upon the full complement of needles by rotary knitting to form a tubular leg portion constituting a continuation of said calf. 80

11. The method of knitting a fashioned stocking, which consists in knitting upon a portion of a circular series of needles by reciprocating knitting, a selvaged strip constituting the foot and ankle portions of the stocking, then in knitting a selvaged strip upon gradually increasing series of needles to form a calf fashioned at one side only and as a continuation of said ankle, the edges of said foot, ankle and calf portions being subsequently united by a seam extending along one side of said stocking, and in knitting upon the full complement of needles a section of tubular fabric as a continuation of said calf and constituting the upper leg portion of the stocking. 85

12. The method of making a fashioned stocking, which consists in knitting upon a portion of a circular series of needles, a selvaged strip constituting the foot and ankle portions of the stocking, then in continuing the knitting upon a series of said needles that is gradually increased in number at one end to form the calf portion of said stocking as a continuation of said ankle, and subsequently stitching together the edges of said several sections to form a seam along one side only of the stocking. 90

65 13. A stocking blank having foot, ankle

and calf portions formed in a continuous strip by reciprocating knitting, said calf portion being fashioned along the edge 24, the edges 14 and 15, 21 and 22, 24 and 25, respectively, of said foot, ankle and fashioned calf portions being stitched together to form a continuous seam extending along one side only of the stocking, the stocking being otherwise seamless. 70

14. That method of knitting a fashioned stocking which consists in knitting the toe of a stocking by narrowing and widening, then upon an incomplete circle of the same series of needles knitting the foot portion by a reciprocating motion to form a fabric 80 selvaged at opposite edges along one side only of the foot, then knitting the heel by a narrowing and widening operation, then knitting a portion of the leg wholly by reciprocating motion to form opposite selvaged edges for a seam at one side only of the stocking, and thereafter knitting the upper portion of the stocking. 85

15. That method of knitting a fashioned stocking which consists in knitting the toe 90 of a stocking by narrowing and widening, then upon an incomplete circle of the same series of needles knitting the foot portion by a reciprocating motion to form a fabric 95 selvaged at opposite edges along one side 95 only of the foot, then knitting the heel by a narrowing and widening operation, then knitting a portion of the leg wholly by reciprocating motion to form opposite selvaged edges for a seam at one side only of the stocking, and thereafter knitting the upper portion of the leg of the stocking by circular knitting. 100

16. That method of knitting a stocking which consists in knitting the toe, then knitting the foot upon an incomplete circle of the same set of needles to form two selvaged edges to be seamed together along one side only of the foot, then knitting the heel upon a portion of the same set of needles, then knitting the main portion of the leg wholly by reciprocating knitting upon an incomplete circle of the same set of needles so as to provide two selvaged edges to be seamed together at one side only of the leg, 110 and during the knitting of said leg portion fashioning the fabric at one only of said selvaged edges, and finally in knitting the upper part of the leg portion wholly by circular knitting. 115 120

17. A fashioned stocking having widened and narrowed heel and toe pockets, a foot having selvage edges at one side thereof only, and a leg having selvage edges at one side thereof only, said edges being a continuation of the selvage edges of the foot, said selvage edges being seamed together. 125

In testimony whereof, I have signed my name to this specification.

GEORGE P. BOSWORTH.
